UNITED STATES PATENT OFFICE.

JAMES H. DOOLEY, OF EAST ORANGE, NEW JERSEY, ASSIGNOR TO ADDOMETER CORPORATION, OF NEW YORK, N. Y., A CORPORATION OF DELAWARE.

ACCUMULATOR FOR CALCULATORS.

1,232,011.

Specification of Letters Patent.

Patented July 3, 1917.

Application filed July 28, 1915. Serial No. 42,278.

To all whom it may concern:

Be it known that I, JAMES H. DOOLEY, a citizen of the United States, and a resident of East Orange, in the county of Essex and State of New Jersey, have invented certain new and useful Improvements in Accumulators for Calculators, of which the following is a specification.

One of the objects of the present invention is to provide in a calculator including a transfer mechanism, improved means for actuating the restoring member, whereby it will be moved to cause the transfer to take place at the initial portion of the return movement of a side bar or main actuating member of the machine.

Another object of the invention is to provide means for actuating the restoring bar of a transfer mechanism from an actuating member that moves back and forth; and means for moving the adding pinions relative to the rack bars to engage and disengage the same, which latter means include a member that upon special operation of the machine to change the normal timing of the said engagement and disengagement of the pinions, will disable the connections for shifting the restoring bar.

In the accompanying drawings illustrating embodiments of my invention, Figure 1 shows in side elevation the left hand side of the machine with the means for controlling the transfer restoring rod, and associated parts. Fig. 2 is an elevation of the moving means for the transfer rod, at the right hand side of the machine. Fig. 3 is a view of some of the parts of Fig. 1, showing the relative positions at the end of the forward stroke of the pitman. Fig. 4 is a view of the parts shown in Fig. 3 in a further advanced stage. Fig. 5 shows one of the arms on the restoring bar. Fig. 6 shows one of the pawls. Fig. 7 shows one of the levers. Fig. 8 is a plan view of the restoring bar and attached arms with adjacent parts of the machine; and Fig. 9 shows the frame for the pinions.

As shown in the drawings 20 represents the side plate of the left hand side of an adding machine, and in Fig. 2 is shown a portion 21 of a similar side plate on the opposite side. These plates are provided with guiding means for a restoring bar 22, that extends across between the plates, and has

secured at its extremities transversely thereto, arms 23 and 24. The guiding means shown comprise slots 25 and 26 in the side plates respectively that extend substantially horizontally. By suitable means the arms 23 and 24 are moved endwise and cause the restoring bar 22 to be moved back and forth of the machine, and transversely of its length. This is the usual movement of the restoring bar in an adding machine.

Means are provided in connection with a main operating member that moves back and forth or oscillates, whereby at the initial portion of the return movement of the member, after being advanced, the arms or one of them is engaged to shift the restoring bar; and at the final portion of the said return movement, the arms are caused to move in the opposite direction to shift the restoring bar to its former position.

As shown, the arm 23 is provided with an abutment 27 at its rear end, in the form of a notch at one corner, that is engaged by a pin 28 on a lever 29 pivoted to the side plate 20. This lever 29 is caused to oscillate by reason of the back and forth movement of the said actuating member. In the form shown the side bar or pitman 30 is reciprocated from a crank 31 fast to a main rock shaft 32 of the machine. At the rear the pitman 30 is supported by a crank 33 from a shaft 34 extending across the machine. A pin 35 on the pitman 30 rides in the slotted end 36 of the lever 29 and the lever is oscillated by the reciprocation of the pitman. It will be understood that the restoring bar 22 can oscillate in the guiding slots 25 and 26 to permit swinging of the arms 23 and 24. A coil spring 37 connects the arm 23 with a suitably located pin 38 that will draw the arm 23 downward as well as rearward, and the arm is normally held in engagement with the pin 28 on the lever 29. A pawl 39 is pivoted on the side plate 20 at its rear, and its free forward end is moved upward against the arm 23, by reason of the pin 38 being located on this pawl. In the lower edge of the arm 23 is a shoulder 40 engaged by the pawl when the arm is moved forward from its normal position. On the opposite side of the machine most of these parts are duplicated as will be seen in Fig. 2. A pitman 41 is caused to reciprocate simultaneous with the pitman 30, by means

not set forth herein. A lever 42 identical with the lever 29 is provided that is oscillated by this pitman, and a pin 43 on this lever engages a notch 44 in the arm 24. A pawl 45 corresponding to the pawl 39 is provided and a coil spring 46 is stretched between this pawl and the arm 24. On this side a coil spring 47 is fast between the arm 24 and a stationary pin 48 on the side plate 21. The latter will have an additional effect of swinging the arm 24 downwardly to engage the pin 43; and since the arm 23 is also fast to the restoring bar this arm will move simultaneous therewith. It will be noticed that the restoring bar 22 engages a toothed lever 4 that forms part of a transfer mechanism. It will be seen that this lever when the restoring bar moves to the other end of its slot as indicated in Fig. 4, is swung to the position indicated in broken lines. And it will be understood that if the toothed lever is controlled by a spring or other member it will be returned to former position when free to move, upon retraction 25 of the restoring bar. When the pitman 30 is moved forward to the position indicated in Fig. 3, the lever 29 will move rearward to bring its pin 28 to engage the abutment 27 of the arm 23, and likewise the pin 43 will engage the abutment 44 on the opposite side on the frame 24; the several springs connected with these arms serving to move the arms downwardly for such engagement. Upon return movement of the pitmen the 30 arms will start to move forward and the restoring bar will advance in the slots 25 and 26. But this short movement of the restoring bar will take place at the initial portion of the return movement of the pitmen and levers. Just before the restoring bar reaches the end of these guide slots, extensions 50 and 51 on the arms 23 and 24 respectively will strike stops 52 and 53 on the side plates, that will cause the restoring bar to rock on its axis to swing the rear ends of these arms upward and away from the pins 43 and 28 on the side levers. This will permit the continued rearward movement of the two levers 29 and 42 as the pins on the levers will move under the arms, as indicated in Fig. 4. But just previous to the release of the arms 23 and 24 from the lever pins, the pawls 39 and 45 will move to engage the abutments 40 and 54 on the arms 23 and 24 respectively, that will prevent at this stage retraction of the arms and restoring bar by the springs 37 and 46, as indicated in Fig. 4. The continued retraction of the pitmen and levers 29 and 42 will bring the pins 28 and 43 thereon into engagement with lugs 55 and 56 on the pawls 39 and 45 respectively and shift the pawls away from the shoulders on these arms; see Figs. 1 and 2. This will permit the retraction of the arms 60 and restoring bar by the springs 37 and 46.

The toothed levers 4 are thereby permitted to be shifted by their controlling springs or other means.

At certain operations of an adding machine it is unnecessary to shift the restoring bar while the pitmen have the usual reciprocation. Therefore it is desirable to provide means to disable some of these parts. As shown I provide a lever 57 suitably pivoted, and arranged to be engaged when any one of three special keys 1, 2 and 3 are depressed, whereby the lever is shifted to engage a pin 49 on the arm 23. By this means the arm 23, also arm 24, are swung upward and held from engagement with the pins 80 on the levers 29 and 42, when the latter are swung by the two pitmen. In the arrangement shown this lever 57 also performs another function. On the side plate 20 is pivoted a lever 58 whose upper end connects by 85 stud 69 with a suitable frame 10 carrying the numeral pinions 5, by which lever the pinions are moved to and from the rack bars 6, and to and from the toothed levers 4. The lever 57 is shown as pivoted on the lever 58, and the forward end of the lever 57 carries a pin 60 arranged to engage abutments 61 and 62 formed by a slot in the pitman 30. At the latter part of the forward movement of the pitman 30 this pin 90 will strike the abutment 61 and the lever 57 will swing the lever 58 to shift the pinions. At the latter part of the return of the pitman 30 abutment 62 will strike the pin 60 and again shift the lever 58 to return the 100 pinions to former position. The rear end 59 of the lever 57 is normally free from the pin 49, and does not interfere with the engagement of the arm 23 with the pin 28 on the lever 29. The special keys 1, 2 and 3 105 engage and depress a swinging lever 63, and the latter carries a bent lever 64 whose extremity is adjacent a pin 65 on the lever 57. By this means when either of these keys is depressed the lever 57 is rocked and 110 engages the pin 49 on arm 23 to shift the arms away from engagement with the pins on the levers 29 and 42. But when a fourth key 66 is depressed the lever 64 is rocked away from the pin 65, and the means for 115 moving the restoring bar is not thereby disabled. This key is the non-print key of the machine, and it is desired to have the adding mechanism operate as usual, when such key is depressed.

In order to hold the lever 58 and the frame in the two positions of engagement of the numeral pinions, I provide a locking member in the form of a lever 85 having a tooth 86 on its extremity that is pressed upward by a spring 87 to alternately engage notches 88 and 89 in the lower end of the lever 58. It will be seen that this tooth 86 has parallel sides with an angular extremity. The notches 88 and 89 are substan- 120 125 130

tially angular, but have at the outer portion of each a straight or vertical wall extending perpendicular to the end of lever 58, for the purpose of engaging parallel side edges of the tooth 86. This will lock the lever in the two desired positions.

Having thus described my invention, what I claim is:

1. Device for operating the transfer restoring member of a calculator, comprising a rod extending across the machine, an arm secured to each end of said rod transversely thereto, said rod and arms being supported to move back and forth to effect the transfer control and restoring movement, a side bar on each side of the machine arranged to reciprocate, a swinging lever on each side of the machine connected with the side bars respectively to be swung by the reciprocation thereof, said arms being engaged by said levers when swung on the initial part of the return movement of the side bars to thereby advance the arms and rod, means for returning the arms and rod, a latch for each arm, a spring for pressing each latch against its arm, each arm having an abutment arranged to be engaged by the latch after said advancement of the arms and rod by the swinging levers, means for releasing the arms from said levers upon engagement of the latches and arms during initial return movement of the arms, whereby further return movement of the arms is prevented at such stage, and means for shifting said latches at the latter portion of the return movement of the side bars and levers to permit return of said arms and rod to former and normal position.
2. Device for operating the transfer restoring member of a calculator, comprising a rod extending across the machine, an arm secured to each end of said rod transversely thereto, said rod and arms being supported to move back and forth to effect the transfer control and restoring movement, a side bar on each side of the machine arranged to reciprocate, a swinging lever on each side of the machine connected with the side bars respectively to be swung by the reciprocation thereof, said arms being engaged by said levers when swung on the initial part of the return movement of the side bars to thereby advance the arms and rod, means for returning the arms and rod, a latch for each arm, a spring for pressing each latch against its arm, each arm having an abutment arranged to be engaged by the latch after said advancement of the arms and rod by the swinging levers, means for releasing the arms from said levers upon engagement of the latches and arms during initial return movement of the arms, whereby further return movement of the arms is prevented at such stage, means for shifting said latches at the latter portion of the return movement of the side bars and levers to permit return of said arms and rod to former and normal position.
3. Device for operating the transfer restoring member of a calculator, comprising a rod extending across the machine, an arm secured to each end of said rod transversely thereto, said rod and arms being supported to move back and forth to effect the transfer control and restoring movement, a side bar on each side of the machine arranged to reciprocate, a swinging lever on each side of the machine connected with the side bars respectively to be swung by the reciprocation thereof, said arms being engaged by said levers when swung on the initial part of the return movement of the side bars to thereby advance the arms and rod, means for returning the arms and rod, a latch for each arm, a spring for pressing each latch against its arm, each arm having an abutment arranged to be engaged by the latch after said advancement of the arms and rod by the swinging levers, means for releasing the arms from said levers upon engagement of the latches and arms during the initial return movement of the arms, whereby further return movement of the arms is prevented at such stage, means for shifting said latches at the latter portion of the return movement of the side bars and levers to permit return of said arms and rod to former and normal position, a set of special keys on the machine, a swinging bar engaged by said keys when depressed, a lever on said swinging bar, means connected with said latter lever to shift the arms out of position for engagement with said swinging levers upon depression of any of the special keys, and a separate key arranged to engage said swinging bar to depress it, said lever on the swinging bar being engaged by said separate key and thereby shifted to prevent said disabling movement of the arms.
4. Device for operating the transfer restoring member of a calculator, comprising a rod extending across the machine, an arm secured to each end of said rod transversely thereto, said rod and arms being supported to move back and forth to effect the transfer control and restoring movement, a side bar on each side of the machine arranged to reciprocate, a swinging lever on each side of the machine connected with the side bars respectively to be swung by the reciprocation thereof, said arms being engaged by said levers when swung on the initial part of the return movement of the side bars to thereby advance the arms and rod, means for returning the arms and rod, a latch for each arm, a spring for pressing each latch against its arm, each arm having an abutment arranged to be engaged by the latch after said advancement of the arms and rod by the swinging levers, means for releasing the arms from said levers upon engagement of the latches and arms during initial return movement of the arms, whereby further movement of the arms is prevented at such stage, means for shifting said latches at the latter portion of the return movement of the side bars and levers to permit return of said arms and rod to former and normal position.

- each latch against its arm, each arm having an abutment arranged to be engaged by the latch after said advancement of the arms and rod by the swinging levers, means for releasing the arms from said levers upon engagement of the latches and arms during initial return movement of the arms, whereby further return movement of the arms is prevented at such stage, said latches being engaged by said levers to release the arms at the latter portion of the return movement of the side bars and levers to permit return of said arms and rod to former and normal position.
5. Device for operating the transfer restoring member of a calculator, comprising a rod extending across the machine, a notched arm secured to each end of said rod transversely thereto, said rod and arm being supported to move back and forth to effect the transfer control and restoring movement, a side bar on each side of the machine arranged to reciprocate, a swinging lever on each side of the machine connected with the side bars respectively to be swung by the reciprocation thereof, a stud on each of the levers that engage in said notched arms when swung on the initial part of the return movement of the side bars to thereby advance the arms and rod, means for returning the arms and rod, a latch for each arm, a spring for pressing each latch against its arm, each arm having an abutment arranged to be engaged by the latch after said advancement of the arms and rod by the swinging levers, an extension on each arm, a stop engaged by each extension to swing the arm upon engagement of the latches and arms during initial return movement of the arm, whereby further return movement of the arms is prevented at such stage, said latches being engaged by said lever studs and released at the latter portion of the return movement of the side bars and levers to permit return of said arms and rod to former and normal position.
6. Device for operating the transfer restoring member of a calculator, comprising a rod extending across the machine, an arm secured to each end of said rod transversely thereto, said rod and arms being supported to move back and forth to effect the transfer control and restoring movement, an actuating member on each side of the machine arranged to be reciprocated, said arms being engaged by said members on the initial part of the return movement thereof to advance the arms and rod, means for releasing the arms and rod, a latch for each arm, a spring for pressing each latch against its arm, each arm having an abutment arranged to be engaged by the latch after said advancement of the arms and rod by the said actuating members, means for shifting said latches at the latter portion of the return movement of the said actuating members to permit return of said arms and rod to former and normal position.
7. Device for operating the transfer restoring member of a calculator, comprising a rod extending across the machine, an arm secured to each end of said rod transversely thereto, said rod and arms being supported to move back and forth to effect the transfer control and restoring movement, an actuating member on each side of the machine arranged to be reciprocated, said arms being engaged by said members on the initial part of the return movement thereof to advance the arms and rod, means for returning the arms and rod, a latch for each arm, a spring for pressing each latch against its arm, each arm having an abutment arranged to be engaged by the latch after said advancement of the arms and rod by the said actuating members, means for releasing the arms from said members upon engagement of the latches and arms during initial return movement of the arms, whereby further return movement of the arms is prevented at such stage, means for shifting said latches at the latter portion of the return movement of the actuating members to permit return of said arms and rod to former and normal position.
8. Device for operating the transfer restoring member of a calculator, comprising a rod extending across the machine, an arm secured to each end of said rod transversely thereto, said rod and arms being supported to move back and forth to effect the transfer control and restoring movement, an actuating member on each side of the machine arranged to be reciprocated, said arms being engaged by said members on the initial part of the return movement thereof to advance the arms and rod, means for returning the arms and rod, a latch for each arm, a spring for pressing each latch against its arm, each arm having an abutment arranged to be engaged by the latch after said advancement of the arms and rod by the said actuating members, means for releasing the arms from said members upon engagement of the latches and arms during initial return movement of the arms, whereby further return movement of the arms is prevented at such stage, means for shifting said latches at the latter portion of the return movement of the said actuating members to permit return of said arms and rod to former and normal position.

normal position, a set of special keys on the machine, a swinging bar engaged by said keys when depressed, a lever on said swinging bar, means connected with said latter lever to shift the arms out of position for engagement with said actuating member upon depression of any of the special keys, and a separate key arranged to engage said swinging bar to depress it, said lever on the swinging bar being engaged by said separate key and thereby shifted to prevent said disabling movement of the lever.

9. Device for operating the transfer restoring member of a calculator, comprising, a rod extending across the machine, a notched arm secured to each end of said rod transversely thereto, said rod and arms being supported to move back and forth to effect the transfer control and restoring movement; an actuating member on each side of the machine arranged to be reciprocated, a stud on each of said members that engage in said notched arms when swung on the initial part of their return movement to thereby advance the arms and rod, means for returning the arms and rod, a latch for each arm, a spring for pressing each latch against its arm, each arm having an abutment arranged to be engaged by the latch after said advancement of the arms and rod by the actuating members, an extension on each arm, a stop engaged by each extension to swing the arm upon engagement of the latches and arms during initial return movement of the arms, whereby further return movement of the arms is prevented at such stage, said latches being engaged by said lever studs and released at the latter portion of the return movement of the actuating members, to permit return of said arms and rod to former and normal position.

10. In an adding machine, the combination with accumulating mechanism, including rack bars, adding pinions that are bodily movable to and from the rack bars, transfer mechanism for the adding pinions including a restoring bar, an actuating member on the machine that is reciprocated at each operation thereof, means including a shiftable connecting member arranged to move the pinions to and from the rack bars by the normal engagement of said member with the said actuating member, means for causing the reciprocating member to effect the shifting of the restoring bar to cause its coöperation with the transfer mechanism, a key on the machine to produce a special operation thereof, and means for releasing said shiftable connecting member from the actuating member upon operation of said key, said connecting member being arranged to disable said shifting means for the restoring bar upon its release from the actuating member.

65 11. In an adding machine, the combina-

tion with accumulating mechanism, including rack bars, adding pinions bodily movable to and from the rack bars, transfer mechanism for the adding pinions including a restoring bar, a pitman on the machine 70 that is reciprocated at each operation thereof, transfer mechanism for the pinions including a restoring rod extending across the machine, an arm secured to one end of the restoring rod transversely thereto, said rod 75 and arm being supported to move back and forth to effect the transfer control and restoring movement, a lever connected with said pitman to be swung thereby when reciprocated, said arm being engaged by said lever on the initial part of the return movement thereof, whereby to advance the arm and rod, a latch for said arm, a spring for pressing said latch against the arm, the arm and latch having engaging means that serve 80 to hold the arm in advanced position when shifted by said lever, means for releasing the arm from said lever upon engagement of the latch and during initial return movement of the arm by the lever to prevent 85 further return of the arm at such stage, means for releasing said latch and arm at the latter portion of the return movement of said pitman to permit return of the arm and rod to normal position, a lever arranged to 90 move the pinions to and from the rack bars, a control lever pivoted on said pinion-shifting lever, a stop on the control lever, abutments on the pitman arranged to engage said stop at the end portion of the advance and of the return movements respectively of the pitman whereby to shift the pinions to and from the rack bars, a key on the machine for producing a special operation thereof, and means for causing the depression of said key to shift said control lever to free its stop from said abutments and prevent shifting of the pinions, said control lever when so shifted by the key being arranged to shift said restoring rod arm 100 to prevent its movement by its control lever.

12. Device for operating the transfer restoring member of a calculator, comprising a rod extending across the machine, an arm secured to one end of such rod transversely thereto, said arm and rod being supported to move back and forth to effect the transfer control and restoring movement, an actuating member on the machine that is moved back and forth at each operation thereof, 115 said member being arranged to engage said arm at the initial portion of the return movement to shift the arm and rod, means for causing the swinging of said arm upon its said movement by the actuating member 120 to release the arm from the member and permit the continued movement of the member free from the arm, a latch arranged to engage said arm when released from the actuating member by its swinging movement, 130

said latch being engaged by the actuating member at the final portion of its return movement to release the arm from the latch, and means for returning the arm and rod to normal position when released from the latch.

13. In a transfer device for an adding machine, the combination of a restoring bar having a pair of transverse arms at its extremities, guiding means for the bar and arms to permit the bar to move back and forth in a path transverse to its length, means for engaging the arms to reciprocate the bar in its guiding means, and means for causing an axial movement of the bar and swinging of the arms to release the arms from the actuating means.

14. In a transfer device for an adding machine, the combination of a restoring bar having a pair of transverse arms at its extremities, guiding means for the bar and arms to permit the bar to move back and forth in a path transverse to its length,

means for engaging the arms to reciprocate the bar in its guiding means, means for causing an axial movement of the bar and swinging of the arms to release the arms from the actuating means, and means for swinging the arms and bar on its axis to move the arms out of range of said actuating means.

15. In a calculator, the combination of a frame mounted to swing, a set of adding pinions and disks carried by the frame, a pivoted lever connected with the frame to move it back and forth, means for swinging said lever, and a locking arm for said lever provided with a tooth having an angular extremity with adjacent parallel edges, said lever being provided with a pair of adjacent angular notches and with parallel walls on the outer portions of the notches respectively arranged to engage said parallel edges of the said tooth.

JAMES H. DOOLEY.
